UNITED STATES PATENT OFFICE.

EMERY B. SWEETSER, OF BROOKLYN, NEW YORK.

SALTCELLAR.

1,352,701.

Specification of Letters Patent. Patented Sept. 14, 1920.

Application filed June 12, 1916. Serial No. 103,308.

To all whom it may concern:

Be it known that I, EMERY B. SWEETSER, a citizen of the United States, and a resident of Brooklyn, county of Kings, State of New York, have invented certain new and useful Improvements in Saltcellars, set forth in the following specification.

This invention relates to sprinkling dispensers of the type usually employed in connection with salt, black pepper, paprika and the like.

An object of my invention is to provide for the dispensing of a pulverulent material such as salt or pepper in a satisfactory manner and the provision of an improved container for storing and dispensing such material. The principal object of my invention is to improve the method of closing a non-corrosive, perforated dispensing cap 20 upon a non-corrosive hollow containing body.

The above will be more clearly understood from the illustrative embodiment of my invention described in the following specification which should be read in connection with the accompanying drawings forming a part hereof, in which like characters designate corresponding parts in the several figures, and in which Figure 1 is a vertical section with parts shown in elevation of an embodiment of my invention; Fig. 2 is a perspective view of the body portion of my dispenser drawn to half scale; Fig. 3 is a perspective view of the disk or cap of my dispenser drawn to half scale; and Fig. 4 is a perspective view of the clamping metal shell of my dispenser drawn to half scale.

In the drawings A indicates the body of my dispenser which may conveniently be molded or cast from glass or other suitable vitreous material. It has a glass base portion 1 which may be suitably ornamented as by cutting. The body also has a vertical, cylindrical shell 2 with an open top 3 and is formed with threads 4 located at a considerable distance below the open top 3, preferably at or near the base portion 1. A disk B suitably cut from a portion of oyster shell or other sea shell is suitably formed as to size and configuration to form a dispensing cap having perforations 5 and an annular seat 6 to fit snugly upon the seat 3 and a marginal flange 7 preferably depressed below the surface 8 of the cap B. A sheet metal shell C may be spun into cylindrical

form with an internal annular flange 9 to take over the flange 7 of the cap B. It is to be understood that the flange 7 is functionally nothing more than an internal gripping means and is not necessarily limited in form to a continuous flange. The lower portion of the cylindrical shell C is formed with threads 10 adapted to take over the threads 4 of the body portion A. The internal diameter of the sheet metal shell C is preferably greater than the external diameter of the cylindrical glass shell 2. A certain amount of play is therefore permitted to the top portion of the sheet metal shell C so that irregularities in the cap B may be compensated and the threads 10 located at a considerable distance from the cap B and top of the cylindrical shell 2 when yielding slightly will give a multiple movement in the locality of the gripping means 9. This feature has considerable advantage in effecting a tight closure of the cap B upon the top portion A. The threads 4 and 10 also accommodate various thicknesses of disk B. There is a further advantage in the positioning of the threads at a material distance from the cap B. When the shell adapted to hold the cap in place is threaded in the immediate locality of the cap, any irregularity in the threads is manifest in its entirety at the flange gripping the cap in place so that, as a result, the cap is clamped to its seat more firmly at one locality than another. When the threads are at a material distance away from the cap and the shell is loose about the part 2, as in this invention, the pull exerted by the threads is quite uniformly distributed and the shell and the cap may shift slightly so that the flange 9 clamps the cap 8 to its seat 6 substantially uniformly throughout its entire periphery. This prevents salt working through under the cap to cause corrosion.

When filling the dispenser it is taken apart as shown in Figs. 2, 3 and 4, when any or all of the parts may be thoroughly, independently cleaned. The body portion A may be readily filled and the entire structure quickly assembled.

What I claim and what I desire to secure by United States Letters Patent is:

A sprinkling dispenser for pulverulent material comprising a hollow body having an opening at the top and a surrounding upwardly directed seat, external screw threads 110 a material distance below said seat and an

external portion between said threads and said seat free from shell engaging means; a perforated dispensing cap overlying and seating upon said seat; an external shell 5 having inwardly extending means for gripping said cap, fitting freely and loosely about said external portion of said body free from shell engaging means and hav-

ing screw threads for engaging said screw threads on said body to clamp said cap upon 10 said seat with a self-adjusting uniform pressure about said seat.

In witness whereof I have signed my name to this specification, this 10th day of June, 1916.

EMERY B. SWEETSER.
